[57] CLAIM

The ornamental design for a parts separator, as shown and described.

DESCRIPTION

FIG. 1 is a front perspective view of a parts separator, showing my new design;

FIG. 2 is an elevational view of one side thereof, the opposite side being a mirror image;

FIG. 3 is a top plan view thereof;

FIG. 4 is a bottom plan view thereof;

FIG. 5 is a rear view thereof;

FIG. 6 is a front view thereof;

FIG. 7 is a front perspective view thereof, similar to FIG. 1 but to a reduced scale.

The broken lines in FIG. 7 are merely intended to illustrate the environment in which the article is found and form no part of the design.
